UNITED STATES PATENT OFFICE.

CHARLES JULIUS KLEIN, OF NEW YORK, N. Y., ASSIGNOR TO RALPH ABRAHAM SCHOENBERG, OF NEW YORK, N. Y.

ATTACHMENT-PLUG.

No. 845,712.

Specification of Letters Patent.

Patented Feb. 26, 1907.

Application filed April 21, 1906. Serial No. 312,964.

To all whom it may concern:

Be it known that I, CHARLES JULIUS KLEIN, a citizen of the United States, residing in the borough of Manhattan, in the city, county, and State of New York, have invented certain new and useful Improvements in Attachment-Plugs, of which the following is a specification.

This invention relates to electrical connections, and more particularly to electrical connections of the class customarily known as "connection-plugs," and it has for its object to provide improvements of the character referred to which shall be superior in simplicity and inexpensiveness of construction and positiveness and convenience in operation and general efficiency and which shall possess superior advantages with relation to the method of connection of and for the protection of the conductors or conductor cord or cable.

I will now describe my invention with reference to the accompanying drawings and then point out the same in appended claims.

In the drawings, Figure 1 is a central longitudinal sectional view of a connection-plug embodying the invention. Fig. 2 is a top plan view of the same. Fig. 3 is a transverse sectional view of the same, taken upon the line 33, Fig. 1, looking in the direction of the connected arrows. Fig. 4 is a similar view taken upon the line 44, Fig. 1, and looking in the direction of the downwardly-pointed arrows. Fig. 5 is a similar view taken upon the line 55, Fig. 1, and looking in the direction of the upwardly-pointed arrows. Fig. 6 is a central longitudinal view of a modified form of construction, and Fig. 7 is a top plan view thereof.

Corresponding parts in all the figures are denoted by the same reference characters.

Referring with particularity to the drawing, the improved electrical connection or connection-plug comprises two separable members A and B, which are joined together or separated from each other upon the line 44, Fig. 1, said two members being jointly provided with operative connection means C, which join the two members together in swiveled relation, but which still provide for convenient and ready relative separation of the

members, the two members so joined together being adapted for connection with the receiving device, such as a plug-socket. (Not shown.)

The circuit wires or conductors which are led into connection with the connection-plug are illustrated in the drawing as consisting of two separate conductor-wires D and E, respectively, and said wires are directly connected with the member B, being brought therefrom into electrical connection, respectively, with two circuit members F and G, respectively, which latter circuit members are carried by the member A. Electric connections H constitute a path from the conductor E to the circuit member F, and electric connections K establish a path from the conductor D to the circuit member G.

A preferred form of construction, operative connection, and relative arrangement of parts and members of a connection-plug comprising the invention as illustrated in the accompanying drawing is as follows: The body member A comprises a generally-cylindrical body portion 6, provided with the customary inclosing threaded metallic shell 7 for connection with the customary threaded socket, and said body 6 is provided with a central longitudinally-extending metallic stem, pin, or screw 8. The end portion of the body portion 6 adjacent to the body member B is provided with an annular chamber 9, in which is arranged a metallic annulus or annular bead 10 of convex interior curvature. The bead 10 is electrically connected with the shell 7 by a metallic screw 11, and the shell 7, screw 11, and bead 10 constitute jointly the circuit member G. The screw 8 holds to the end portion of the body portion 6 adjacent to the body member B a metallic plate 12, provided with a plurality of outwardly-projecting curved spring-prongs 13, and said plate 12, spring-prongs 13, and screw 8 comprise the circuit member F. The inner end 14 of the screw 8 and the shell 7 are adapted for connection with circuit members or connection parts in the plug-receiving socket in the customary manner. The body member B comprises an annular body portion 15, of suitable insulating material, which is adapted to abut against the chambered

end portion of the body portion 6 of the body member A when the members A and B are operatively connected, the central opening 16 in said body portion 15 registering with 5 the chamber 9 in the body portion 6. A perforated cap 17, provided with an interior chamber 18, fits over and surrounds the annular body portion 15, being detachably connected with the latter by a plurality of 10 screws 19, which pass through said cap 17 and take into the body portion 15. The electrical connections H comprise a binding-screw 20, (with which the conductor 8 is electrically connected,) connected with the body portion 15, and a connection-plate 21, which is held to the body portion 15 by the binding-screw 20 and projecting interiorly of the chamber 18 within the cap 17, being provided centrally thereof with an annular head 22, formed and arranged to embrace within 15 itself, in electrical contact therewith, the curved spring-prongs 13 upon the plate 12 when the body members A and B are fitted together. The electrical connections K comprise a binding-screw 23, with which the conductor D is electrically connected, and a curved metallic plate 24, arranged diametrically opposite to the binding-screw 20, and which is bound centrally upon the body portion 15 by the binding-screw 23, and provided with a plurality of downwardly-ranging curved metallic spring-prongs 25, which extend through the central opening 16 in the body portion 15 and into the annular chamber 9 when the members A and B are operatively connected, closely binding upon and against the metallic bead 10 in electrical contact.

It will be seen from the above that the conductor E is connected with the circuit member F through the binding-screw 20, the connection-plate 21, and the head 22 thereof, which engage with the prongs 13. It will also be seen that the conductor D is electrically connected with the circuit member G by the binding-screw 23, the metallic plate 24, and the prongs 25, which contact with the metallic bead 10.

As most clearly shown in Fig. 1, the prongs 13, because of their curved or irregular form and their spring quality, constitute, with the head 22 and the plate 21, locking means M, and the prongs 25, because of their curved or irregular formation and their spring quality, constitute, with the bead 10, locking means N, both said locking means M and N acting to bind together the members A and B in such manner as to permit of convenient and easy relative separation of the members 60 A and B by merely pulling the member B away from the member A and that said members A and B are held operatively together by said locking means M and N in

such relation that said members may be relatively separated as above set forth and 65 are when operatively connected capable of turning one with relation to the other upon the longitudinal axis of said members, the members A and B thus being separably held together by the locking means M and N in 70 swiveled connection.

Referring to Figs. 6 and 7, the body member A, which is in all other respects similar in its construction to that described with respect to the other figures, is provided with a 75 grip member O, whereby it may be manipulated in connecting the member A with and disconnecting the member A from its receiving-socket or other fixture. The member O is preferably formed of insulating material 80 and may consist of a ring 26, of hard rubber or other suitable material, which is preferably formed with an interior annular slot 27, which receives the projected outwardly bent or flanged edge portion 28 of the metallic 85 shell 7, which surrounds the body portion 6, said shell being for this purpose suitably projected beyond said body portion at the end thereof which is provided with the chamber 9.

The method of use and advantages of the 90 improvements herein described will be readily understood from the foregoing description, taken in connection with the accompanying drawing and the following statement: The body members A and B, with their contained 95 and component parts, features, and members, are readily joined together by bringing the body portion 15 to bear upon the body portion 6 in proper registration, so that the prongs 25 shall enter the chamber 9 and bind tightly upon the bead 10 and the prongs 13 shall pass through and bind upon the head 22 of the plate 21. With the body member A screwed into the customary socket 105 the body member B with its connected conductors D and E may be readily turned in either direction upon the body A, said members A and B now being swiveled together, and such turning of the body member B upon the body member A does not in any way interfere with the maintenance of the normal 110 electrical circuit conditions in the conductor E, the electrical connections H and circuit member F, on the one hand, and in the conductor D, the electrical connections K, and the circuit member G on the other hand.

The conductors D and E are readily connected with the binding-screws 23 and 20, respectively, by removing the screws 19 and detaching the chambered and perforated cap 17 from the body 15, the conductors D and E being first led through the perforation or opening in the cap 17.

The convenience and quickness with which 125 the body members A and B can be connected and disconnected by use of the locking means

M and N, herein described, are apparent. The inclusion of those locking means in the electrical connection features of the device results in simplicity of construction and the 5 obviation of duplication of parts.

With reference to the modified construction shown in Figs. 6 and 7 the grip member O enables the body member A to be readily manipulated in connecting the same with 10 and disconnecting the same from the receiving fixture and effectually insulates the hand so employed from the remaining parts of the body member A, together with what electrical conditions there may be existant 15 therein.

The simple swivel connection between the body members A and B prevents torsion of the conductors D and E or their equivalent substitute or substitutes in the manipulation 20 of any current-consuming devices or mechanism with which the said conductors may be electrically connected, providing that flexible connection between the current-consuming device and the connection-plug which 25 most effectually conserves the best working conditions and the prevention of injury to the conductors.

Whereas I am aware that in the prior art there are examples of connection-plugs members of which are swivelly connected and also examples of connection-plugs in which members are detachably connected, I am not aware that connection-plugs or attachment-plugs are found comprising two members which are at the same time detachably 30 and swivelly connected. According to this invention the members are detachably connected in such manner that they may be detached or separated one from the other without distinct manipulation of any locking means, such as screws, nuts, &c. The locking means which are employed and which are comprised in the circuit members of the device are so constituted as to yield in their 35 holding function to the exertion of relatively slight strain or pressure. In other words, in the use of this invention to connect the two members and set up the working-current-carrying conditions the two members are simply 40 brought together under pressure, and to relatively separate the two members and terminate current-carrying conditions the two members are simply urged or drawn apart without any distinct disconnecting 45 manipulation of minor or auxiliary parts.

I do not desire to be understood as limiting myself to the specific construction, relative arrangement, and connection of parts and members herein described, but reserve 50 the right to vary the same in adapting the same to varying conditions of use without departing from the spirit of the invention or the terms of the following claims.

Having thus described my invention, I claim and desire to secure by Letters Patent—

1. An electrical attachment-plug, comprising two separably and swivelly operatively connected body members jointly provided with means for maintaining electrical circuit 70 conditions, and locking means detachably uniting said body members and comprised within said means for maintaining electrical circuit conditions.

2. An electrical attachment-plug, comprising two body members separably and swivelly operatively connected, one of said body members being provided with circuit members, and the other of said body members being provided with electrical connections 75 respectively adapted for electrical contact with said circuit members, and locking means detachably uniting said body members.

3. An electrical attachment-plug, comprising two body members separably and swivelly operatively connected, one of said body members being provided with circuit members, and the other of said body members being provided with electrical connections 80 respectively adapted for electrical contact with said circuit members, and locking means detachably uniting said members, said locking means being comprised within said electrical connections and circuit members.

4. An electrical attachment-plug, comprising two body members, one of which is provided with two circuit members, said body member being provided with a chambered portion and with a metallic bead in said 90 chambered portion, constituting one of said circuit members; the other of said body members being provided with electrical connections adapted for contact respectively with said circuit members, said latter body member being provided with a plurality of metallic spring-prongs constituting one of 95 said electrical connections, and arranged for electrical contact and locking engagement with said metallic bead carried by the former 100 body member whereby said body members are detachably and swivelly operatively connected.

5. An electrical attachment-plug, comprising two body members, one of which is provided with two circuit members, one of said circuit members comprising a plurality of spring-prongs, the other of said body members being provided with electrical connections adapted respectively for electrical contact with said circuit members, the latter body member being provided with an annular metallic plate arranged for electrical contact and locking engagement with said spring-prongs whereby said body members are 115 detachably and swivelly operatively connected.

6. An electrical attachment-plug, comprising two separably and swivelly operatively connected body members, one of said body members being provided with circuit members, and the other of said body members being provided with electrical connections and with binding-screws adapted to hold electrical conductors, said electrical connections being adapted for electrical contact with said

circuit members, and locking means whereby said members are detachably united.

In testimony whereof I have signed my name to this specification in the presence of two subscribing witnesses.

CHARLES JULIUS KLEIN.
